DESIGN FOR A DOLL

Charlotte Crockett Young, Concord, N. H.

Application November 16, 1948, Serial No. 149,661

Term of patent 7 years

(Cl. D34—4)

To all whom it may concern:

Be it known that I, Charlotte Crockett Young, a citizen of the United States, residing in the city of Concord, county of Merrimack, and State of New Hampshire, have invented a new, original, and ornamental Design for a Doll, of which the following is a specification, reference being had to the accompanying drawing, forming part thereof, and in which:

Fig. 1 is a side view; and

Fig. 2 is a front view of the doll showing my new design.

I claim:

The ornamental design for a doll, as shown.

CHARLOTTE CROCKETT YOUNG.
